1 Claim

ABSTRACT OF THE DISCLOSURE

Apparatus for dyeing and the treatment of loosely wound sleeves comprising a horizontal working tank, a horizontal perforated material holder for the sleeves within the tank, an extractor disc slidably mounted on the holder, operating rods extending parallel to the holder and fixed to the disc and a second disc slidably mounted on the holder and detachably secured to the opposite ends of the rods.

The dyeing and related treatments of various natural, artificial and synthetic threads and fibres, for example those intended for knitted goods, haberdashery and the like, are at present particularly delicate and difficult since, in order to obtain the required qualities in respect to uniformity and swelling, the fibres can only be treated in the form of a skein weighing approximately 400 gr. which implies, inter alia, the necessity of employing numerous and particularly conscientious workers. In fact, since the skeins are conventionally supplied in bundle form by the spinner, they must firstly be unpacked, put on a bar and opened. These loaded bars are then mounted on a material-holder, after which the spread of the skeins must again be checked. After the material-holder has been in the working tanks or chambers, the skeins must be removed from the bars and gathered together in hanks, each weighing approximately 1 kg., in order to pass to the operation of drying without heating. After this operation, the hanks must be separated and the skeins are replaced individually on the bars in order to pass to the operation of drying. Finally the skeins must be individually handled in order to unravel and check them, before being made into bundles and packed for dispatch.

Besides the numerous manual operations which it requires, this process also includes the disadvantage that it seriously limits the speed of circulation of the baths, due to the danger of felting of the fibres in skein form. Finally the ground surface area occupied by an installation applying the above conventional process is extremely great, since each treatment tank for example requires a spreading area which occupies by itself three or four times the surface area of the tank, if the maximum profit-earning potential of the material is to be obtained.

It must be stated that processes for dyeing threads which are less difficult and more rapid, for example processes using cones or beams, are known. These techniques cannot be applied to the threads intended for knitted goods, haberdashery and the like since the threads which are wound on cones or beams have virtually no freedom to permit the fibres to swell.

It has also already been proposed that skeins should be dyed in loose form, being placed in porous wrappings and arranged in baskets which are then immersed in the tanks. However this technique can only be employed when the requirements in respect of quality are relatively modest, such as for example for the threads for carpets. In fact skeins which are thus arranged and placed in tanks are compressed, which reduces the freedom for the fibres to expand and can also cause the threads to break.

It has also already been proposed that the threads should be wound in the form of sleeves weighing approximately 3 kg. under porous and elastic wrappings. This

2

method is of advantage in that it facilitates handling and unwinding. On the other hand, when such sleeves are conventionally placed in the treatment baths, they bunch and lose their homogeneity so that the desired uniformity and swelling cannot be systematically obtained. It must be stated here that in the present description, the term "sleeve" indicates a winding or coil in cylindrical form with a cylindrical axial bore and without a support such as a cone, reel or the like.

10 The aim of the present invention is to simplify considerably the dyeing and related treatments of natural, artificial and synthetic threads and fibres, in various forms such as threads, textiles and the like which, after these treatments, must meet rigorous requirements in respect of uniformity, swelling, structure, etc.

An advantage of the present invention is to permit the baths to be renewed substantially more frequently than in conventional installations, which permits a wider range of coloring agents and products for related treatments to be used.

20 Another advantage of the present invention is that it requires only a relatively small quantity of water, which permits substantial economies to be made with respect to coloring agents, heat etc. . . .

25 Yet another advantage of the invention lies in the treatment of textured and elastomer threads which avoids detrimentally affecting the qualities of elasticity, swelling etc. . . .

30 The invention includes installations which are mainly characterized by at least one substantially horizontal working tank provided with internal means for supporting and maintaining at least one sleeve so that said sleeve is arranged horizontally. The internal means can with advantage be arranged to support a plurality of sleeve arranged end to end, in one or more lines.

35 Other features and advantages of the present invention will be more clearly apparent from the embodiments described hereinafter by way of non-limitative example, with reference to the accompanying drawings in which:

40 FIG. 1 shows a side elevation of an installation arranged to carry out the process according to the present invention;

45 FIG. 2 is an end elevation of the installation illustrated in FIG. 1;

FIG. 3 shows in cross-section on an enlarged scale the material-holder to be used in the tank of the installation shown in FIGS. 1 and 2;

FIG. 4 is an end view;

50 FIG. 5 is a transverse cross section of another embodiment of the working tank,

And FIGS. 6 and 7 are installation diagrams showing a plurality of working tanks.

The installation to carry out the above defined process, and shown in FIGS. 1 to 4, substantially comprises a frame 1, supporting, inter alia, a horizontal working tank 2. The height of this frame 1, or the distance between the loading door 3 and the ground, depends on the height of the conventional trucks used for handling the material, so that the contents of said tank can be tipped directly

55 into the trucks. Arranged in the tank 2 is an axial material-holder 4 mounted at one of its ends on the end of said tank 2, the material-holder being hollow and being connected to a pipe 5 of the bath circulation circuit. The other end of this circulation circuit comprises a pipe 6 connected toward the end of said tank, for example, to a dispersion ring (not shown). The circuit to which the pipes 5 and 6 belong, also comprises a pump 7 driven by a motor 8, a heat exchanger 9 and a container 10 acting as a compression chamber provided with a heating stirrer and a coil.

60 A set of taps 15 permits the container 10 to be isolated during operation and to be opened after cooling; the outlet

12 of this container is connected to the intake of the circulating pump 7.

The working tank 2 is also provided with a safety valve 13 and a pipe 14 with a variable flow tap 11 which permits a continuous leak to be formed, ensuring that air is eliminated in the course of treatment.

The hollow material-holder 4 is provided with a plurality of perforations 16, the diameters of which may increase from the end of the tank toward the free end of said material-holder (not shown), in order to make the flow of solution uniform along said material-holder when the bath is passed through the pipe 5. An extractor-separator 17 comprising a disc 18 which is preferably perforated, can slide along said material-holder 4. The ends of two operating rods 19 are fixed on the disc 18, the other ends of the rods ending in a handle 20. These rods 19 are intended to co-operate with two notches 21 in a second separator disc 22 which also slides along the material-holder 4 and the position of which thereon can be adjusted by means of a pin 23.

To facilitate loading the sleeves, illustrated in diagrammatic form at 24, a removable cone 25 can be fitted on to the free end of the material-holder 4.

Operation of this installation, as far as the present invention is concerned, is substantially as follows. The sleeves supplied by the spinner are firstly unpacked, then threaded one after the other on to the material-holder 4 from which the disc 22 has previously been removed. The disc 22 is replaced at the end of the loading operation, being held in place by the pin 23, and the rods 19 are then engaged in said slots 21. The door 3 of the tank is then closed and treatment of the fibres can begin. Since this door is provided with a sealing means (not shown), the installation permits treatment to be under pressure and at high temperature. The treatment bath can circulate in the two directions, from the interior to the exterior or from the exterior to the interior of the material, the bath being introduced into the tank 2 either by means of the pipe 5 through the inside of the material-holder 4 or by means of the pipe 6. Since the sleeves 24 are supported on the inside by the material-holder 4 and on the outside by the elastic mesh net described hereinbefore, the original homogeneity of the sleeves is retained, i.e. there is practically no movement of the turns of the winding forming each of the sleeves; the speed of circulation of the treatment baths can be very high without there being any danger of felting, which permits difficult coloring agents to be used.

A gate valve 26 by-pass mounted on the intake and the delivery of the circulation group permits the flow rate of the bath circulating through the material to be varied.

When the treatment is concluded and the tank 2 is emptied, the door 3 of the tank is opened, the rods 19 are released from the notches 21 and the disc 22 is removed. With a truck (not shown) having been positioned under the mouth of the tank from which the door 3 has been released, the operator can take hold of the two handles 20 and by pulling on them, can move the disc 18 toward the outlet of the tank, which causes each of the sleeves 24 to fall successively into the truck. These sleeves can then be passed as they are to the drying without heat-

ing and the drying operations, to arrive finally at dispatch, where the operation of checking, which used to require a long and careful preliminary coiling operation, is reduced to a simple surface inspection of each sleeve.

It is obvious that the tank 2 could have an internal diameter sufficient to contain a plurality of material-holders 4, for example seven material-holders arranged as illustrated in FIG. 5.

Moreover the above described installation could be provided with a plurality of tanks, for example two in the case of FIG. 6 and four in the case of FIG. 7. In these two examples, the treatment tanks can either operate together or separately. Thus, in the embodiment illustrated in FIG. 6, isolating gate valves indicated at 27 permit one

15 of the tanks to be isolated from the bath circulation circuit while in the example illustrated in FIG. 7, the valves 28 and 29 permit one or two of the four tanks of the installation to be isolated.

It is obvious that the above described installations can 20 be widely modified without going outside the scope of the present invention as long as they retain at least one substantially horizontal treatment tank arranged to receive sleeves of fibres, arranged end to end in one or more lines parallel to the longitudinal axis of the tank.

What I claim is:

1. The installation for dyeing and treating various natural and synthetic threads and fibers having the shape of sleeves which are loosely wound without continuous contact between adjacent threads, which comprises a horizontal cylindrical working tank, a perforated material holder mounted horizontally within said tank and having one end connected with one end of said tank, an extractor disc slidably mounted upon said holder, two operating rods extending parallel to said holder and having adjacent ends 30 fixed to said disc, handles connected to the opposite ends of said rods, and a second disc slidably mounted upon said holder adjacent the other end thereof and having notches cooperating with said opposite ends of the rods.
